(57) **CLAIM**

The ornamental design for an ultrasound probe, as shown and described.

DESCRIPTION

FIG. 1 is a perspective view of an ultrasound probe showing my new design,

FIG. 2 is a front view of the ultrasound probe,

FIG. 3 is a back view of the ultrasound probe,

FIG. 4 is a top view of the ultrasound probe,

FIG. 5 is a bottom view of the ultrasound probe,

FIG. 6 is a right side view of the ultrasound probe; and,

FIG. 7 is a left side view of the ultrasound probe.

In FIGS. 1-4, the broken lines depict portions of the ultrasound probe that form no part of the claimed design.
